UNITED STATES PATENT OFFICE.

PETER B. BELCHES, OF ST. LOUIS, MISSOURI.

STARTING MECHANISM FOR EXPLOSIVE-ENGINES.

1,086,638.

Specification of Letters Patent.

Patented Feb. 10, 1914.

Application filed May 27, 1912. Serial No. 699,994.

To all whom it may concern:

Be it known that I, PETER B. BELCHES, a citizen of the United States, residing in the city of St. Louis and State of Missouri, have 5 invented certain new and useful Improvements in Starting Mechanism for Explosive-Engines; and I do declare the following to be a full, clear, and exact description of the invention, such as will enable others skilled 10 in the art to which it appertains to make and use the same.

This invention relates to improvements in starting mechanism for explosive engines.

One object of the invention is to provide 15 a starting device of this character in the form of a compressed air motor having means whereby the motor is engaged with the fly wheel of the engine and the fly wheel thus operated to start the explosions in the 20 cylinder.

Another object of the invention is to provide means whereby the motor may be converted into a pump and operated by the engine to compress air into a suitable tank 25 whereby this air may be employed for operating the motor to start the engine.

A further object is to provide means whereby a predetermined pressure of air will be automatically maintained in the tank. 30 With these and other objects in view, the invention consists of certain novel features of construction, and the combination and arrangement of parts as will be more fully described and claimed.

35 In the accompanying drawings; Figure 1 is a front view of my improved engine starting mechanism showing the same in position on the frame of a motor vehicle and in engagement with the fly wheel of the engine, 40 a portion of said wheel being shown in dotted lines; Fig. 2 is a side view of the mechanism shown in Fig. 1; Fig. 3 is a vertical sectional view taken substantially on the line 3—3 of Fig. 2; Fig. 4 is a top plan view of 45 the mechanism showing the casings of the air controlling valves in section; Fig. 5 is an enlarged irregular vertical sectional view through the casings of the air controlling valves and through the cylinder of the piston 50 which controls the position of the motor, taken on the line 5—5 of Fig. 4; Fig. 6 is a vertical sectional view taken at right angles to Fig. 5 and on the line 6—6 of Fig. 4; Fig. 7 is a side view of the opposite side of the

motor from that shown in Fig. 2; Fig. 8 is a 55 central vertical sectional view of the motor and the valve casing and valve thereof; Fig. 9 is a horizontal sectional view through the valve casing of the motor with the valve removed and showing more particularly the 60 arrangement of the air inlet and discharge ports of the valve casing; Fig. 10 is a vertical sectional view through a portion of the motor and its valve casing and valve taken on the line 10—10 of Fig. 8 and illustrating 65 the position of the valve at this end of the casing when the motor is operating as a pump; Fig. 11 is a similar view through the opposite end of the valve casing and the valve taken on the line 11—11 of Fig. 8 illustrating 70 the position of this end of the valve when the motor is working as a pump; Fig. 12 is a view similar to and taken on the same line as Fig. 10 illustrating the position of the valve at this end of the casing when the 75 motor is working as a motor, and Fig. 13 is a view similar to and taken on the same line as Fig. 11 illustrating the position of the valve at this end of the casing when the motor is working as a motor. 80

In the embodiment of the invention illustrated, I provide a motor comprising a cylindrical casing 1 in which is revolvably mounted an eccentrically disposed cylindrical piston 2, one side of which forms a fluid tight 85 engagement with the adjacent inner surface of the cylinder between the inlet and discharge ports thereof. In the piston 2 on opposite sides of the center thereof are longitudinal recesses or sockets 3. The recess 3 on one side of the center of the piston opens through one side thereof, while the recess on the opposite side of the center opens through the opposite side of the piston as shown. Slidably mounted in the recesses 3 are the 90 wings or blades 4 of the piston, said blades being forced outwardly and yieldingly held in a projected position by coiled springs 5 arranged between the inner ends of the blades and the inner ends of the recesses 3. 100 The outer edges of the blades 4 when thus projected form a fluid tight engagement with the inner surfaces of the cylinder.

On the cylinder 1 of the motor is arranged a valve casing 6 in which is disposed a rotary valve 7 by means of which the passage of the air to and from the cylinder of the motor is controlled. The valve chamber

communicates with the cylinder near one end thereof by an air inlet port or passage 8 and near the opposite end thereof by an inlet port or passage 9. In one side of the valve chamber 6 is formed an air inlet port 10 through which air is drawn into the motor when the latter is operated as a pump and in the opposite side at the opposite end of the valve chamber is an air exhaust port 10' through which air exhausts when the motor is employed as a motor. In the same side of the valve chamber but at the opposite end thereof from the port 10' is arranged a combined inlet and discharge port 11, said port serving as an inlet port when the motor is used as a motor and as a discharge port when the motor is used as a pump. The combined inlet and discharge port 11 of the valve is connected by a flexible air conducting pipe 12 with a compressed air tank 13 into which air is compressed by the motor when the latter is operated as a pump and from which the air is taken to drive the motor when employed as such.

At a suitable position on the valve casing of the motor is arranged an apertured lug 14 which is pivotally connected to a motor supporting plate 15 bolted or otherwise suitably secured to one of the side bars 16 of the frame of the machine. The plate 15 is further supported and braced at its outer end by an inclined brace rod 17 connected at one end with the upper side of the frame bar 16 and at its lower end to a lug 18 on the end of the plate 15 as shown. The bracing and supporting rod 17 has arranged thereon a sleeve 19 one end of which engages the lug 18 and the other end the upper side of the bar 16. By providing the bracing rod 17 with the sleeve 19 having its ends engaged with the lug 18 and side bar of the frame it will be seen that the inner end of the plate 15 is securely braced and fastened against movement in either direction.

On the plate 15 is arranged a cylinder 20 having therein a piston 21 between which and the lower end of the cylinder is arranged a coiled spring 22 the pressure of which is applied to the piston to force it forwardly in the cylinder. The piston 21 is provided with a piston rod 23 which extends through one end of the cylinder and through the plate 15 and is connected at its outer end with one arm 24 of a bell crank lever 25 which is fulcrumed on a bearing lug 26 on the lower side of the frame bar 16. The other arm 27 of the bell crank lever is connected by a connecting rod 28 to a lug 29 on the adjacent side of the motor casing 1 whereby when the bell crank lever is rocked in one direction or the other the motor casing will be swung on its pivotal connection with the plate 15 in a corresponding direction.

The motor when arranged in the manner described is disposed adjacent to one side of a fly wheel 29^a of the engine and on the shaft 30 of the motor is fixed a driving pulley 31 which when the motor is swung in one direction or the other by the bell crank 70 lever 25 is adapted to be engaged with or disengaged from the fly wheel 29^a of the engine so that when the motor is used as a motor the fly wheel will be driven to start the engine and when the motor is used as a pump, said fly wheel will operate the motor as will be readily understood.

To the compressed air tank or reservoir 13 is connected an air conducting pipe 32 which is connected to a check valve casing 33 to 80 which is also connected the upper end of the flexible air conducting pipe 12 leading from the valve casing on the motor. The valve casing 33 has arranged therein a check valve 34 which opens toward the compressed air 85 reservoir or against the pressure of the air therefrom. Slidably mounted in the casing 33 of the valve 34 is a valve operating stem 35 one end of which extends through and projects a suitable distance beyond one end 90 of the valve casing and is adapted to be engaged by an operating mechanism hereinafter described. The pipe 32 of the air tank or reservoir is also connected by a branch air conducting pipe 36 to a valve 95 casing 37 arranged on the upper end of the cylinder 20 and having therein an air inlet port 38 and an air discharge port 39, said ports communicating with the cylinder 20. Also arranged at a suitable position in the valve casing 37 is an air discharge or release port 40. In the valve casing 37 is slidably mounted a cylindrical valve 41 which is adapted to open and close the ports 38 and 39 thereby controlling the inlet and discharge of air to and from the cylinder 20. Arranged in the outer end of the valve casing 37 and engaged with the valve 41 is a light coiled spring 42 the purpose of which will be hereinafter described. 100 Also arranged in the outer portion of the valve casing 37 is a valve operating rod or stem 43 one end of which is engaged with the end of the valve 41 and the other end of which projects through the end of the 105 valve casing and is adapted to be engaged by an operating mechanism hereinafter described.

The valve 7 in the casing 6 on the motor is provided with an operating stem 44 which 120 projects through one end of the valve casing and has fixedly secured thereto a valve operating lever 45 which is normally held in engagement with a stop 46 on the end of the casing by a bowed spring 47 one end of 125 which is secured to the stop 46 and the other end engaged with the lower side of the lever as shown in Fig. 1.

Suitably mounted on the bottom of the body of the automobile to which the motor is applied or to any other suitable part of the machine is a foot operating lever 48 one end of which projects up through the bottom of the machine and has arranged thereon a foot treadle 49. At a suitable position on the foot lever 48 is a valve operating rod 50 the lower end of which extends downwardly 5 in position to engage the outer end of the valve operating lever 45 on the stem 44 of the valve 7 whereby when the foot lever is depressed the valve operating lever 45 will be actuated to shift the valve 7 from its 10 normal position to a position wherein the compressed air from the tank or reservoir 13 will be admitted through the pipe 12 to the motor cylinder to drive the piston therein in the proper direction for causing the 15 pulley on the piston shaft to operate the fly wheel of the engine whereby the latter is cranked. On the foot lever 48 are also arranged valve operating lugs 51 and 52 which are adapted to respectively engage the valve 20 stems 35 and 43 of the valves 34 and 41 in the valve casings connected with the air pipe of the compressed air reservoir whereby said valves are properly operated for admitting the compressed air from the reservoir to the 25 air conducting pipe 12 and cutting off the air from the reservoir to the cylinder 20 and releasing the air in said cylinder whereby the spring 22 is permitted to project the piston 21 and piston rod 23 thereby actuating 30 the bell crank lever 25 to shift the motor 1 in position to engage the pulley 31 on the shaft thereof with the fly wheel of the engine.

By constructing and arranging the motor 1 and the air controlling mechanism connected therewith in the manner described it will be seen that when the valve 7 of the motor is in its normal position or the position in which it is held by the spring 47 and the motor is in position for engaging 45 the pulley thereof with the fly wheel, the motor will act as a pump and the piston thereof will be driven by the fly wheel thereby forcing air through the air conducting pipe 12 to the valve casing 33 and past the 50 check valve 34 through the pipe 32 to the reservoir, said valve 34 being opened automatically by the pressure of the air as each charge is forced past the same by the pump. As hereinbefore stated the motor is held in 55 position for engaging the pulley with the fly wheel of the engine by the action of the spring 22 in the cylinder 20, said spring projecting the piston 21 and through the same the piston rod 23 actuating the bell 60 crank lever 25 and connecting rod 28 to shift the motor to the position stated. The spring 22 in the cylinder 20 will continue to act and hold the motor in engagement with the fly wheel of the engine until the pressure of air being pumped into the reservoir 13 is 65 sufficient to open the valve 41 against the pressure of its spring 42 and to overcome the pressure of the spring 22 in the cylinder 20. When the pressure of the air in the reservoir is sufficient to overcome the pressure of the spring 22 the piston 21 will be projected against the pressure of the spring thereby causing the piston rod 23 to actuate the bell crank lever in a reverse direction thereby swinging the motor back and disengaging the pulley 31 thereof from the fly wheel of the engine thereby stopping the pumping operation. As long as a sufficient pressure is maintained in the reservoir 13 to overcome the action of the spring 22 the motor will be held out of engagement with the fly wheel of the engine. As soon however as the pressure in the reservoir is reduced the spring will again project the piston and automatically swing the motor into engagement with the fly wheel of the engine, thus operating the motor to pump more air into the reservoir until the pressure is restored. It will thus be seen that the air pressure in the reservoir 13 is automatically maintained. 70 75 80 85 90 95 100 105 110 115 120 125

When it is desired to employ the motor as a motor for cranking the engine the foot lever 48 is depressed, thus bringing the valve operating rod 50 into engagement with the lever 45 whereby the latter will be actuated to turn the valve 7 in the proper direction for permitting the air from the air pipe 12 to enter the motor cylinder. This air operates to drive the piston and the pulley 31 in the proper direction for operating the fly wheel 29. When the foot lever is depressed to engage the rod 50 with the valve operating lever 45 the lug 51 is simultaneously engaged with the stem 35 of the check valve 34 and said stem projected to 105 open the check valve 34 thereby permitting the air from the reservoir to enter the air conducting pipe 12 which conducts the air to the motor. The operation of the foot lever 48 also engages the lug 52 with the stem 110 43 of the valve 41 thereby operating said valve to close the air inlet port 38 in the valve casing 37 thus cutting off the pressure of air from the reservoir to the cylinder 20 and simultaneously opening the discharge 115 port 39 which will permit the air in the cylinder 20 above the piston 21 to escape through the valve casing 37 and release port 40. As soon as the pressure of the air is thus cut off from the cylinder 20 and the air remaining therein released, the spring 22 will immediately project the piston in said cylinder thereby causing the piston rod 23 to actuate the bell crank lever 25 in the proper direction for swinging the motor into 120 position for engaging the pulley thereon with the fly wheel of the engine so that the action of the pulley is applied to the fly

wheel for cranking the engine. As soon as the engine has been started the foot lever is released thus permitting the spring 47 to actuate the lever 45 and to return the valve 7 to its normal position which instantly changes the motor to a pump, so that the action of the fly wheel is now applied to the pulley to operate the same and the piston of the motor in the proper direction for forcing 10 more air back into the air reservoir in the manner described and until the pressure in the reservoir has been restored to its normal degree whereupon the motor will be automatically disengaged from the fly wheel in 15 the manner described.

From the foregoing description taken in connection with the accompanying drawings, the construction and operation of the invention will be readily understood without 20 requiring a more extended explanation.

Various changes in the form, proportion and the minor details of construction may be resorted to without departing from the principle or sacrificing any of the advantages of 25 the invention as shown.

Having thus described my invention, what I claim is:

1. An engine starter comprising a suitably supported compressed air motor, a 30 valve to control the admission of air to the motor, a drive pulley fixed on the shaft of the motor, a spring to shift said motor into position for engaging said pulley with the fly wheel of the engine, a compressed 35 air reservoir, means actuated by the pressure of air in said reservoir to overcome the pressure of said spring and disengage the motor from the fly wheel, means adapted to be actuated by the operator to shift 40 said valve to a position for admitting compressed air from said reservoir to said motor, whereby the latter is operated to drive said fly wheel, and means to simultaneously release the air pressure from said motor 45 shifting spring to permit the latter to shift the motor into operative engagement with the fly wheel of the engine.

2. An engine starter comprising a combined compressed air motor and air pump, a 50 compressed air reservoir, a valve casing connected with said motor and with said reservoir, a valve in said casing to control the admission of the air from the reservoir to the motor and from the motor to the reservoir, whereby the motor is operated as such to drive the engine, and whereby when the motor is driven by the engine said motor will pump air into the reservoir, a drive pulley on the shaft of the motor, a motor 55 shifting mechanism to engage said pulley with the fly wheel of the engine when the air pressure in the reservoir is reduced, means to normally hold said valve in position to permit the motor to pump air into 60 the reservoir when driven by the engine, and

means to shift said valve to admit compressed air to the motor and to simultaneously release said motor shifting mechanism.

3. An engine starter comprising a suitably supported compressed air motor, a 70 drive pulley fixed on the shaft of the motor, a valve casing connected with the motor, an air controlling valve in said casing, a compressed air reservoir, an air conducting pipe to connect said valve casing with said reservoir, a check valve arranged in said pipe, a compressed air cylinder connected with said reservoir, a valve to control the admission and discharge of air to and from the cylinder, a piston in said cylinder adapted 75 to be retracted by the compressed air admitted to the cylinder from said reservoir, a spring for projecting said piston, a bell crank lever connected with said piston and with the motor, whereby when the air is 80 released from said cylinder the piston will be projected by said spring and the motor automatically shifted to engage the pulley thereof with the fly wheel of the engine, and whereby when the piston is retracted by 85 the compressed air admitted to the cylinder, the motor will be shifted to disengage the pulley from the fly wheel, and means to operate the controlling valve of the cylinder to release the air from said cylinder, thereby 90 permitting the spring therein to shift the motor into engagement with the fly wheel of the engine.

4. An engine starter comprising a suitably supported compressed air motor, a 100 drive pulley fixed to the shaft thereof, a valve casing connected with the motor, an air controlling valve in said casing, a spring actuated lever to normally hold said valve in position to permit the motor to act as a 105 pump, a compressed air reservoir, an air conducting pipe to connect said valve casing with said reservoir, a check valve arranged in said pipe, a valve operating stem, a compressed air cylinder connected with 110 said reservoir, a valve to control the admission and discharge of air to and from said cylinder, an operating stem connected to said last mentioned valve, a piston in said cylinder adapted to be retracted by the compressed air admitted to the cylinder and from said reservoir, a spring for projecting said piston, a bell crank lever connected with said piston and with the motor, whereby 115 when the air is released from said cylinder 120 the piston will be projected by this spring and the motor automatically shifted to engage the pulley thereof with the fly wheel of the engine and when the piston is retracted by the compressed air admitted to the 125 cylinder the motor will be shifted to disengage the pulley from the fly wheel; a suitably mounted valve operating lever, means carried by said lever to actuate the lever of the air controlling valve of the motor, where- 130

by said valve is turned to admit air to the motor from the reservoir, and means carried by said lever to engage the stems of said check valve and the valve of said compressed air cylinder, whereby said valves are operated simultaneously with the operation of the air controlling valve of the motor.

In testimony whereof I have hereunto set my hand in presence of two subscribing witnesses.

PETER B. BELCHER.
